Primary Examiner—Charles A Rademaker*Assistant Examiner*—Dana L Sipos*(74) Attorney, Agent, or Firm*—Rader, Fishman & Grauer, PLLC(57) **CLAIM**

The ornamental design for an aircraft seat, as shown and described.

DESCRIPTION

FIG. 1 is a top, right perspective view of an aircraft seat showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a bottom, right perspective view thereof.

Portions of the figures that are shown as broken lines are for illustrative purpose only and form no part of the claimed design.
